CLAIM

The ornamental design for a mixer-pourer for drinks, as shown and described.

DESCRIPTION

FIG. 1 is a perspective view of a mixer-pourer for drinks embodying my new design.

FIG. 2 is a top plan view thereof.

FIG. 3 is a bottom plan view thereof.

FIG. 4 is a side elevational view thereof, the opposite side view being a mirror image.

FIG. 5 is a front elevational view thereof.

FIG. 6 is a rear elevational view thereof.

Fig. 1.

Fig. 2.

Fig. 3.

Fig. 4.

Fig. 5.

Fig. 6.
